UNITED STATES PATENT OFFICE

EDWIN H. FISHER, OF PITTSBURGH, PENNSYLVANIA, ASSIGNOR TO FISHER SCIENTIFIC COMPANY, OF PITTSBURGH, PENNSYLVANIA, A CORPORATION OF PENNSYLVANIA

LABORATORY BURETTE HOLDER

Application filed July 16, 1932. Serial No. 622,837.

- This invention relates to burette holders, and it is among its objects to provide holders which positively grip the burette to prevent movement both angularly and vertically of the holder, are quick-acting, of simple and easily used construction, leave the entire burette scale visible, and permit the transmission of light through substantially the entire length of the burette.
- 10 The holders or clamps heretofore used for supporting burettes have been subject to various disadvantages. For example all such holders, whether of the spring, clamp or other type, engage the burette in such a manner as to obscure a substantial portion of its scale divisions, which necessitates moving the burette in the holder to make readings in such obstructed regions. Some types of these holders also form an opaque backing over a substantial vertical height of the burette, thus cutting off the transmission of light through that portion. This makes it difficult to make accurate readings in and adjacent to such portions, since errors may arise from 20 parallax phenomena due to differences in the appearance of the meniscus under transmitted and under reflected light, as is the case where part of the burette scale is shut off from transmitted light.
- 25 Moreover, the burette holders heretofore commercially available have not provided fully satisfactory supporting action. For instance they clamp the burette at a single point, so that the burette may tilt, thus causing errors in reading, or so that the burette may slide upwardly and downwardly in the support. Others may require heavy clamping action such as to endanger the burette, while all clamp types are slow acting, requiring that the jaws be opened to the full width of the burette to insert or remove it, and since the jaws are screw-actuated this is a time-consuming and objectionable operation.
- 35 The holder provided by this invention comprises a backing plate having at one side vertically spaced forwardly extending fixed fingers aligned for vertical contact with one side of a burette, and an arm pivotally connected to the plate to move between the fixed
- fingers. At its extended end the pivoted arm carries a pin, and this arm is impelled continuously toward the fingers to bring its pin into engagement with the side of a burette opposite that engaged by the fixed fingers. 55 Thus the burette is held between generally parallel clamping fingers which positively engage opposite sides of the burette and do not obstruct the scale. Most suitably the pin contacts the adjacent side of the burette at a point intermediate that which is engaged by the fingers, so as to exert an angular clamping thrust, and advantageously the movable arm is positioned rearwardly of the plate with its pin extending forwardly and generally parallel to the fingers. Preferably the fixed fingers are positioned at the ends of vertically spaced fixed arms which project laterally from the backing plate, and a pair of arms are pivotally connected to the rear of the plate and urged one toward each finger to engage the burette in the manner just described. This construction permits 60 transmission of light through substantially the entire scale.
- 65 The invention may be described further with reference to the accompanying drawings, of which Figs. 1 and 2 are a vertical rear elevation and a top plan view, respectively, of one embodiment; Figs. 3 and 4 70 views similar to Figs. 1 and 2, showing the preferred embodiment; and Fig. 5 a side view of the disassembled clamping arms of the holder shown in Figs. 3 and 4.
- 75 The holder may be constructed to support a single burette, although preferably both sides of the plate are constructed in the manner just explained for supporting two burettes. Such an embodiment is shown in 80 the drawings.
- 85 The holder may be constructed to support 90 a single burette, although preferably both sides of the plate are constructed in the manner just explained for supporting two burettes. Such an embodiment is shown in the drawings.
- 95 The embodiment shown in Figs. 1 and 2 comprises a backing plate 1 having at each side a pair of vertically spaced laterally projecting fixed arms 2 the ends of which are bent forwardly to form fingers 3 which preferably are offset, as shown in Fig. 2, to form a sort of cradle for one side of a burette 4, but without obstructing its scale divisions. An arm 5 having a forwardly projecting pin 6 at one end is pivotally connected at its other 100

end to the backing plate, for example by mounting the arm upon a stud 7 projecting rearwardly from plate 1. This permits arm 5 and pin 6 to move between arms 2 for contact with the burette, while leaving the front of the burette fully exposed. A spring 8 acting between the plate and movable arm urges the arm continuously toward one of the fingers.

10 In the use of this embodiment arm 5 is drawn upwardly against the tension of spring 8 to provide sufficient space for insertion of burette 4 between the fixed fingers 3 and pin 6. Upon permitting arm 5 to move downwardly under the spring pressure pin 6 engages one side of the burette and thrusts it against fingers 3. It will be observed that in this embodiment the pin acts between the fingers, and exerts an angular thrust. This 15 is particularly advantageous, for secure clamping of the burette is thereby obtained with relatively light pressures, and the angular forces tend to prevent vertical slippage.

20 The holder may be supported in any desired manner. In the embodiment shown a stirrup 9 receives rod 10 of a ring stand, or the like, the holder being locked in any desired vertical position by a set screw 11, Fig. 2.

25 A further embodiment of the invention is shown in Figs. 3 to 5, in which backing plate 1a is provided at each side with arcuately extending fixed vertically spaced arms 2a each of which is provided with a forwardly 30 extending offset finger 3a adapted, as in the preceding embodiment, to engage one side of a burette 4a. This form embodies two movable arms 5a and 5b projecting laterally from behind plate 1 and provided adjacent their outer ends with forwardly projecting pins 6a. These arms are pivotally mounted at their 35 inner ends upon a common stud 7a, and they are urged apart toward the adjacent fingers by a coil spring 8a whose ends are engaged 40 in studs 15 formed on the arms. As in the preceding embodiment the burette is gripped between fingers 3a and pins 6a. The projecting ends 16 of arms 5a and 5b serve as 45 a convenient gripping means for drawing the arms together against the tension of spring 50 8a.

55 Advantageously the holder is provided with means for limiting inward travel of the movable arms, so that each arm may be uniformly positioned with respect to the fingers 3a and the burette each time a burette is inserted in the holder. In the embodiment shown the arms are provided with projections 60 17 which contact with a stop 18 formed on the rear of the backing plate. This permits each arm to move midway of the fixed arms and fingers, so that when arms 5a and 5b are released they will assume substantially the 65 same relative positions with respect to fingers

3a and the burette. As before, the pins 6a preferably act between the fingers, so that each time a burette is placed in the holder it is positively gripped by uniformly applied thrust of the movable arms.

70 Thus the invention provides burette holders which positively support and position the burettes, and which prevent vertical sliding and angular movements of the burette. In both embodiments the entire scale is free to unobstructed view at all times, and by making the arms narrow only relatively short vertical heights of the burette are cut off from transmission of light. The device is exceptionally quick acting, as will be understood from the description and drawings, and is much more rapid and easy to use than the clamp type holders now in use. If desired, and as is common practice, the burette-engaging pins and fingers may be covered with 80 short lengths of rubber tubing.

85 According to the provisions of the patent statutes, I have explained the construction and mode of use of my invention and have illustrated and described what I now consider to represent its best embodiment. However, I desire to have it understood that, within the scope of the appended claims, the invention may be practiced otherwise than as specifically illustrated and described.

90 I claim:

1. A clear-vision quick-acting burette holder comprising a backing plate having at one side a pair of laterally extending vertically spaced fixed arms provided at their outer ends with forwardly projecting vertically aligned fingers for contact with one side of a burette, a pair of movable arms positioned rearwardly of the plate and pivotally connected at one end thereto to move toward and from each other and said fingers, each of said movable arms being provided at its extended end with a forwardly projecting pin positioned to cooperate with said fingers for holding a burette therebetween, and a spring 100 acting between said movable arms continuously urging them apart toward the adjacent fingers, said fingers engaging one side of a vertically positioned burette and said spring 105 acting on the movable arms urging said pins into engagement with the opposite side of the burette to thereby support the burette positively and with its graduations substantially unobstructed.

110 2. A clear-vision quick-acting burette holder comprising a backing plate having at one side a pair of laterally extending vertically spaced fixed arms provided at their outer ends with forwardly projecting vertically aligned fingers offset to receive one side 115 of a burette, a pair of movable arms positioned rearwardly of said plate and pivotally connected thereto at one end by a single pivot pin at a point intermediate said fixed arms to move toward and from each 120

other and said fingers, each of said movable arms being provided at its extended end with a forwardly projecting pin positioned to cooperate with said fingers for holding a burette therebetween, and a spring acting between said movable arms continuously urging them apart toward the adjacent fingers, said fingers engaging one side of a vertically positioned burette and said spring acting on the movable arms urging said pins into angular engagement with the opposite side of the burette at points intermediate the fingers to thereby support the burette positively and with its graduations substantially unobstructed.

3. A clear-vision quick-acting burette holder comprising a backing plate having at one side a pair of laterally extending vertically spaced fixed arms provided at their outer ends with forwardly projecting vertically aligned fingers offset to receive one side of a burette, a pair of movable arms positioned rearwardly of said plate and pivotally connected at one end to the plate substantially midway between said fixed arms to move toward and from each other and said pins, each of said movable arms being provided adjacent its extended end with a forwardly projecting pin positioned to cooperate with said fingers for holding a burette therebetween, and a spring acting between said movable arms continuously urging them apart toward the adjacent fingers, said fingers engaging one side of a vertically positioned burette and said spring acting on the movable

arms urging said pins into angular engagement with the opposite side of the burette at points intermediate the fingers to thereby support the burette positively and with its graduations substantially unobstructed.

4. A clear-vision quick-acting burette holder comprising a backing plate having at one side a pair of laterally extending vertically spaced fixed arms provided at their outer ends with vertically aligned fingers for contact with a burette, a pair of movable arms disposed rearwardly of the plate and pivotally connected at one end thereto substantially midway of said fixed arms to swing toward and from each other and said pins, means for restricting said movable arms in moving toward each other to a point midway between the fixed arms, each of said movable arms being provided adjacent its extended end with a forwardly projecting pin positioned to cooperate with said fingers for holding a burette therebetween, and a spring acting between said movable arms continuously urging them apart toward the adjacent fingers, said fingers engaging one side of a vertically positioned burette and said spring acting on the movable arms urging said pins into angular engagement with the opposite side of the burette at points intermediate the fingers to thereby support the burette positively and with its graduations substantially unobstructed.

In testimony whereof, I sign my name.
